NICHOLAS A. DOVAS, OF NEW YORK, N. Y.

LID-SUPPORTER.

1,342,325.

Specification of Letters Patent.

Patented June 1, 1920.

Application filed January 19, 1920. Serial No. 352,298.

To all whom it may concern:

Be it known that I, NICHOLAS A. DOVAS, a citizen of the United States, residing at New York, in the county of New York and 5 State of New York, have invented new and useful Improvements in Lid-Supporters, of which the following is a specification.

This invention relates to lid supporters.

Some of the objects of the invention are:

- 10 to produce a comparatively inexpensive device of this character with which the lid of any object may be effectively sustained in various or different open positions; to produce a device which embodies a pair of elements, which co-act to sustain the lid of an object in various or different open positions in virtue of the impingement of certain parts of one of said elements against certain parts of the other of said elements—
- 15 20 the said element being responsive to the movements of the lid to circumvent the impinging action to permit the lid to be moved to a closed position. With these and other objects in view the invention resides 25 in the simplification of a device of this character and in the particular provision and arrangement of parts hereinafter more fully described and illustrated in the accompanying drawings in which:—
- 30 Figure 1 is a sectional elevation illustrating the application of the present invention.

Fig. 2 is a similar view showing the positions, the several parts of the device, as 35 sume when the lid is in open position.

Fig. 3 is a detail view illustrating the manner in which one of the co-acting elements of the device is moved to a predetermined position and the manner in which 40 it is sustained in such position to permit the lowering of the lid to a closed position.

Fig. 4 is a detail view illustrating one of the features of the device.

Fig. 5 is a modified form of the invention. 45 Referring now to the drawing, it will be seen, that there has been shown so much of an object only, which represents one part thereof and another part which represents the lid therefor. It is to be understood 50 that the device is not to be limited to its use to any particular lidded object but that the same may be used upon all kinds of lidded objects.

In the drawing 10 designates one part of 55 an object and 11 its lid which is hinged thereto as at 12. A plate 13 is secured to

the part 10 in any suitable manner and an element 14 is pivotally secured to the plate 13. The element 14 is provided with an aperture 15. An element 16 is carried by 60 the lid 11, and is pivoted as at 17, to an attaching member 18 secured to the lid 11, as shown in the drawing, or in any suitable manner. The element 16 is disposed to extend through, and is, at times movable 65 through the aperture in the element 14. The aperture 15 has dimensions slightly larger than the cross section dimensions—in a plane at a right angle to the side edges—of the element 16, so that in one position of 70 the element 14, the element 16 may freely move through the aperture 15, whereas, in another position of the element 14, the element 16 will be held against movement, in virtue of the impinging action between certain 75 walls of the aperture 15 and the side edges of the element 16. The device embodies co-acting members 19 and 20. The member 19 is carried by the element 14 and the member 20 is carried by the plate 13. 80 As the element 14 is moved on its pivot upwardly to a predetermined degree, the member 19 which is resilient, will frictionally engage the member 20 to sustain the element 14 in a position which will permit 85 the element 16 to move freely through the aperture 15 in a downward direction. The element 16 is at all times permitted to have an upward movement and regardless of any 90 position the element 14 may be in. Moreover, except when the member 19 is in frictional engagement with the member 20, the element 14 is influenced by the action of gravity and invariably assumes the position shown in Fig. 2 of the drawing, in 95 which position of the element 14, the element 16 is prevented from having downward movement, in other words, the relative positions the elements 16 and 14 assume, sets up the impinging action between these 100 parts—the cross sectional area in an oblique plane with respect to the side edges of the element 16 as distinguished from the cross sectional dimensions on a plane at right angles to the side edges of the element 16, is 105 larger. This latter fact, together with the fact that the aperture 15 is slightly larger than the cross sectional dimensions as taken on a plane at right angles to the side edges of the element 16 and smaller than 110 the cross sectional dimensions of the element 16 taken on a plane which is oblique to

the side edges of said element 16, thus permitting the free movement of the element 16 through the aperture 15 in the position of the element 14 shown in Fig. 3 of the drawing and preventing movement of the element 16 through the aperture 15 when the element 14 is in the position shown in Figs. 1 and 2 of the drawing. The element 14 is engageable by a pin 21 carried by the element 16 in the upward movement of said element, to cause the co-action of the members 19 and 20 to sustain the element 14 to permit the downward movement of the element 16 and consequently the closing of the lid. The element 16 is provided with a shoulder 22 formed by cutting away the element. In the downward movement of the element 16 the shoulder 22 engages the upper face of the element 14 to release it from its frictionally sustained position to the action of gravity substantially at the time the lid assumes a closed position in which condition it again permits of the upward movement of the lid.

25 From the foregoing it will be understood that the lid may be moved to various or different open positions and to the most minute degrees; that the lid will be sustained and will be held against being closed except by first moving the lid until the pin 21 engages the element 14 to move the same to its non-impinging position, when the lid may be moved to a closed position. The element 14 is limited in its upward movement since the projection 14^a of said element will engage the member 20 as shown in Fig. 3 of the drawing.

In the modified form of the invention shown in Fig. 5 of the drawing, the equivalent of the element 14 is shown as being of two parts, namely, the part 23 which is fixedly secured and the part 24 is pivoted as at 25 and this part is actuated after the fashion of the complete element 14 of the preferred form of the invention. It will therefore be understood that the only difference in the modification over the preferred form of the invention is that instead of using a one piece element 14, two parts will be used, the co-action of the parts 23 and 24 with the element 26, as in the modification will be identical as regards the result, as that produced by the elements 14 and 16 of the preferred form of the invention.

What is claimed as new is:—

1. In a device as characterized a pair of pivoted elements, one of said elements being frictionally controlled to permit the movement of the other of said elements relatively to the first element, and means for causing the said elements to interlock with each other to prevent the movement of the second element relatively to said first element.
2. In a device as characterized, a pair of

elements, one of said elements being carried by one part of an object and the other of said elements being carried by the lid of said object, the first element being frictionally controlled to permit the movement of the second element relatively to the first element, and means for causing the said elements to interlock with each other to prevent the movement of the second element relatively to the first element as and for the purpose specified.

3. A device of the character described, including a pair of elements, one of said elements being pivoted to one part of a lidded object, the other of said elements being pivoted to the lid of said object, one of said elements being freely movable through the other of said elements in one direction when the lid is being moved to an open position and immovable through said other element in an opposite direction to its first mentioned direction of movement to hold said lid open in different positions.

4. A device of the character described, including a pair of elements, one of which is pivotally attached to one part of a lidded object and the other element being pivotally attached to the lid of said object, an aperture in one of said elements, the other of said elements extending through said aperture, the apertured element being free to gravitate as the element attached to the lid moves upwardly therewith, the lid being held supported in an open position by the impingement of the walls of said aperture against the side edges of the element attached to the lid.

5. A device of the character described, including a pair of elements, one of said elements being pivotally attached to one part of a lidded object, the other elements being pivotally attached to the lid of said object, the lid being held against being closed by the impingement of one element against the other until one of said elements assumes a predetermined position, and means on the element attached to the lid for effecting movement of the other element to the predetermined position as the lid is moved to a predetermined degree, the lid then being permitted to move to a closed position.

6. A device of the class described, including a pair of elements, one of said elements being pivotally attached to one part of a lidded object, the other element being pivotally attached to the hinged lid of said object, the second mentioned element extending through and being movable in an aperture in the first mentioned element, certain walls of said aperture impinging against the side edges of the second mentioned element; and co-acting members which permit the movement of the second mentioned element through the first mentioned element for the return movement of the lid to a closed po-

sition by temporarily sustaining the first mentioned element in a predetermined position.

7. A device of the class described, including a pair of elements, one of said elements being pivotally attached to one part of a lidded object, the other element being pivotally attached to the hinged lid of said object, the second mentioned element extending through and being movable in an aperture in the first mentioned element, certain walls of said aperture impinge against the side edges of the second mentioned element at a predetermined time to hold said second mentioned element against movement and co-acting members which permit the movement of the second mentioned element through the first mentioned element to permit the return movement of the lid to a closed position, one of said members being resilient and being frictionally engageable with the other of said members for so temporarily sustaining the first mentioned element in a position so as to circumvent the impinging action.
8. A device of the class described, including a pair of elements, one of said elements being pivotally attached to one part of a lidded object, the other element being pivotally attached to the hinged lid of said object, the second mentioned element extending through and being movable in an aperture in the first mentioned element, certain walls of said aperture impinge

against the side edges of the second mentioned element, co-acting members which permit the movement of the second mentioned element for the return movement of the lid to a closed position, one of said members being resilient and being frictionally engageable with the other of said members for so temporarily sustaining the other element and to circumvent the impinging action and means on the second mentioned element for moving the first mentioned element out of its friction engagement to the action of gravity.

9. A device of the character described embodying means including an element adapted to assume different positions on one part of a lidded object, and a second element carried by the lid of said object, the said elements co-acting so that in one position of the first mentioned element, said second element is permitted to move in one direction relative to the first mentioned element but is prevented from moving in an opposite direction whereas in another position of the first mentioned element, the second element is permitted to have movement in opposite directions relative to the first mentioned element as and for the purpose specified.

In testimony whereof I have affixed my signature.

NICHOLAS A. DOVAS.
